(57) **CLAIM**

The ornamental design for a multi-effects signal processor, as shown and described.

DESCRIPTION

FIG. 1 is a perspective view of a multi-effects signal processor.

FIG. 2 is a top plan view of the multi-effects signal processor of FIG. 1.

FIG. 3 is a bottom plan view of the multi-effects signal processor of FIG. 1.

FIG. 4 is a rear elevation view of the multi-effects signal processor of FIG. 1.

FIG. 5 is a front elevation view of the multi-effects signal processor of FIG. 1.

FIG. 6 is a left side elevation view of the multi-effects signal processor of FIG. 1; and,

FIG. 7 is a right elevation view of the multi-effects signal processor of FIG. 1.

The broken lines shown in FIGS. 1-4 and 6 are illustrative of environmental features only and form no part of the claimed design.
